UNITED STATES PATENT OFFICE.

JACOB S. MERRITT AND HENRY B. COBURN, OF COVINGTON, VIRGINIA.

RAIL-JOINT.

No. 918,577.

Specification of Letters Patent. Patented April 20, 1909.

Application filed June 30, 1908. Serial No. 441,189.

To all whom it may concern:

Be it known that we, JACOB S. MERRITT and HENRY B. COBURN, citizens of the United States, residing at Covington, in the county of Alleghany and State of Virginia, have invented a new and useful Rail-Joint, of which the following is a specification.

This invention relates to rail joints and its object is to provide a simple device of this character which dispenses with the use of bolts and similar fastening devices and which operates to automatically grip the rails when subjected to a load so that displacement of the rails is prevented and the same are held rigidly while the cars are passing over them.

Another object is to provide a rail joint including fish plates having integral means for engaging the rails.

20 A further object is to provide novel means for tying the parts of the joint together.

With these and other objects in view the invention consists of certain novel features of construction and combinations of parts 25 which will be hereinafter more fully described and pointed out in the claims.

In the accompanying drawings is shown the preferred form of the invention.

In said drawings: Figure 1 is a vertical 30 transverse section through a rail joint embodying the present improvements. Fig. 2 is a section on line A—B, Fig. 1. Fig. 3 is a perspective view of one of the members of the joint.

35 Referring to the figures by characters of reference, 1 and 2 designate oppositely disposed fish plates, each being located longitudinally upon the upper portion of a flange 3 which overhangs the base 4 of a chair. 40 This base is designed to extend under a rail 5 and when it is in this position the flange 3 extends over one of the base flanges of the rail so that the fish plate is enabled to rest close to the web of the rail and between the 45 head and base flange thereof. The base 4 has its upper face inclined downwardly from its free longitudinal edge toward its point of juncture with the flange 3, and the bottom face of said base is correspondingly inclined. Each fish plate has an integral 50 stud 6 extending from the inner face thereof adjacent one end.

A combined brace and bridge plate is designed to be used in connection with the 55 chairs and consists of a metal strip or bar 7 having a jaw 8 at each end, said jaws be-

ing spaced apart a distance equal to the normal distance between the outermost faces of the chairs. As shown in Fig. 1 each jaw has its gripping face preferably curved as 60 indicated at 9 so as to firmly engage the adjoining portion of the chair.

When it is desired to connect two rails by means of the joint herein described one of the fish plates is placed at each side of the 65 meeting ends of the rails so that the base flanges of said rails will rest upon the elevated adjoining edge portions of the bases 4 and will project under the flanges 3. The stud 6 of one of the fish plates will thus 70 project into an opening 10 formed in one of the rails while the corresponding stud of the other fish plate will project into a similar opening in the other rail. The bar 7 is then placed under the two chairs and the 75 jaws slipped longitudinally onto the outer faces thereof. These jaws serve to prevent the two chairs from moving apart more than a predetermined distance. Obviously when the rails are subjected to the weight of a 80 car they will press downward on the elevated edge portions of the bases 1 and the chairs will thus be caused to swing with the jaws 8 as fulcrums. Fish plates 1 and 2 will be pressed tightly upon opposite faces of the 85 rails. It will be seen that this gripping action will increase in proportion to the weight to which the rails are subjected. As the studs 6 project into the rails they will operate to prevent the rails from being drawn 90 apart too far.

It will be seen that a joint such as herein described is very simple, durable, and efficient, can be readily placed in position, and inasmuch as no bolts or similar fastening 95 devices are employed it is practically impossible for the parts to get out of proper position.

As shown in Fig. 2 notches 11 may be formed in the ends of the bar 7 for the reception of spikes whereby the bar can be secured to a tie.

Importance is attached to the fact that the fish plates 1 and 2 do not interfere with the expansion and contraction of the rails 105 but move with the respective rails and between the jaws without, however, releasing the rails.

What is claimed is:

1. A rail joint comprising bases inclined 110 upwardly toward each other, rail-engaging flanges overhanging and integral with the

bases, fish-plates upstanding from the flanges, means upon one of the fish-plates for positively engaging a rail there-between, means upon the other fish-plate for positively engaging a second rail there-between, and means for holding the bases against lateral movement.

2. A rail joint comprising bases inclined upwardly toward each other, flanges overhanging and integral with the bases, fish-plates upon the flanges, a stud upon one of the plates for engaging a rail between the plates, a stud upon the other plate for engaging a second rail between the plates, and means embracing the bases for holding them in a predetermined position.

3. The combination with rails; of depressible supports therefor; fish-plates movable with said supports and actuated thereby to clamp the rails, a stud carried by one of the fish-plates for engaging one of the rails, a stud carried by the other fish-plate for engaging the other rail, and means for holding the supports against lateral movement.

In testimony that we claim the foregoing 25 as our own, we have hereto affixed our signatures in the presence of two witnesses.

JACOB S. MERRITT.
HENRY B. COBURN.
